Inventor
Thomas R. MacMechen
By his Attorney J. W. Parker

UNITED STATES PATENT OFFICE.

THOMAS R. MACMECHEN, OF NEWARK, NEW JERSEY.

AIRSHIP.

Application filed September 3, 1921. Serial No. 498,264.

To all whom it may concern:

Be it known that I, THOMAS R. MACMECHEN, a citizen of the United States, and resident of Newark, in the county of Essex and State of New Jersey, have invented certain new and useful Improvements in Airships, of which the following is a specification.

This invention relates to airships and my improvements are directed toward the production of a novel form of hull structure which combines the qualities of homogeneity, great strength, and relatively light weight.

Hitherto, the general practice in the construction of rigid dirigibles has comprehended the employment of a frame composed of either metallic or wooden longerons, with transverse members or girders of the same material, said frame being covered with an envelope of flexible material, and a number of gas containing ballonettes have been placed within the frame for buoyant lift.

Thus the skeleton or frame only of the so-called rigid dirigible, as known, has been of rigid character, and the constituent elements of the skeleton have necessarily been of such substantial dimensions, to satisfy the requirements for ample strength, as to cause the weight of the fabricated structure, including the envelope and ballonettes, to be excessive to a degree that diminishes the amount of lifting capacity for load and cargo.

It is a fundamental fact that as the volume of gas content rapidly increases in larger sizes of airships, there is an increasingly greater proportion of lift available for fuel and cargo; and this progressive increase of lift, as calculation proves, may continue indefinitely at the same ratio even to the point when eventually the airship reaches a size whereby its empty weight would become practically nothing but for the fact that before this point is attained, the increasing surplus of lift permits it to be utilized to float a more substantial hull built up of solidly joined walls approximately the hulls of ocean ships.

My own experiments and calculations have shown the prime necessity, in the development of the art pertaining to airships, of attaining the highest possible degree of

structural homogeneity, that the hull may be incapable of distortion by the pressures encountered under high propulsive power and by expansion, and I have therefore devised an integral hull, of uniform, homogeneous texture throughout, and wherein the stresses and strains to which the airship is subjected in service are distributed within and absorbed by the entire hull structure.

Broadly my invention consists in the formation of an airship hull entirely of plywood, spiralled parallel strips or plies, in edge abutting or scarfed relationship, being formed into hull contour, successive superposed plies suitably secured together in the fabrication, respectively, having opposite spiral direction.

The plies or laminae are multiplied sufficiently for the production of a hull of adequate strength, and may include an intermediate layer of gas containing material, such as rubberized fabric.

My invention also, optionally comprehends the provision of an outer shell, of less wall thickness, composed of spiral plies similar to those used in the hull formation, and spaced from the main, gas-holding shell or hull.

Said gas shell or chamber is divided by bulkheads, composed of diaphragms, into a number of longitudinal compartments, which thus take the place of the usual ballonettes, said bulkheads each characterized as being impermeable to gas.

The hull and outer shell may be suitably separated to provide a collecting space for gas that seeps through the gas chamber, and the outer shell is provided with dispersion means therefor, to prevent the formation of inflammable mixtures in said space.

Circular beams or girders are arranged within the hull or inner shell, to stiffen it and add to its structural strength, and internal bracing has its securing means in the respective regions of said beams.

In an airship much of the construction material hitherto used, such as metallic or wooden longerons, can be dispensed with, since a very material part of the stresses borne by such longerons or girders is in the case of my invention compensated for in the walls of a solid hull, said walls having a lighter weight than an airship with a skeleton frame as hitherto constructed.

Other features and advantages of my invention will hereinafter appear.

In the drawing:—

Figure 1 is a side elevation of my improved airship.

Figure 2 is a cross-section thereof.

Figure 3 is a detail end view.

Figure 4 is a detail of the mortised joint, and

Figure 5 is a detail of the scarfed joint.

In the construction of my improved rigid dirigible airship I provide a hull or gas holding shell 1 composed of strips 2 and 3 which are respectively arranged in opposite spirals, in the manner of cross-wise laminae. The strips 2 are in parallelism with each other, and have their side edges, as to adjacent strips, in closely connected and secured relation, as with glue, cement or the like, and may have morticed or scarfed joints; and the same is true of the strips 3.

An example of a morticed joint for the strips 2 and 3 is shown in detail in Figure 4, and an example of a scarfed joint is shown in detail in Figure 5.

Each strip 2 and 3 may consist of plywood or may be a single layer of wood.

When the strips 2 and 3 are of plywood the sectional lengths thereof, which must be utilized in the production of an airship hull, have an end projecting ply or plies to interfit with the end projecting ply or plies of an abutting section, to effect a laminated joint therewith. But when the strips 2 and 3 are composed each of a single layer of wood, then the abutting ends of adjacent lengthwise sections are united with morticed or scarfed joints.

Superposed layers of strips 2 and 3 alternate in their spiraled directions, and are multiplied according to the thickness of said strips, for the purpose of building up a wall of suitable rigidity and strength, to thereby constitute an airship hull. Said shell or hull 1, to be gas containing, may have a layer of rubberized fabric, gold-beater's skin or other suitable material, as 4, interposed between adjacent plies formed by the strips 2 and 3, or the shell may be coated on one or both of its surfaces with a suitable fluid composition which is impermeable by gas.

The strips 2 and 3 taper in their width toward the respective ends of the hull, to thereby permit the production of the end portions in their forms of diminishing transverse area.

An outer shell 5 which may be constructed around shell 1, also composed of oppositely spiraled strips 6 and 7 may correspond with the described fabrication of shell 1 from strips 2 and 3: except that the shell 5 is not required to have the same degree of structural strength as shell or hull 1.

Therefore the thickness of wall for the outer shell 5 is considerably less than that of the inner shell or hull 1.

Concentric rings 8, which may be composed of plywood, are disposed suitable distances apart throughout the length of the airship, interiorly of shell 1, to constitute transverse reinforcing means.

Bulkheads, or transverse partitions 9, here shown, composed of fabric, and including means whereby they are rendered non-permeable by gas, are located suitable distances apart, longitudinally, within the shell 1, to provide gas containing compartments, taking the place of ballonettes usually employed with rigid dirigibles. These bulkheads however, besides dividing up the shell 1 into gas containing compartments, are provided with tensional means 11, radiating from the longitudinal axis of the airship, to serve the useful purpose of bracing the shell 5; the rings 8 being disposed in the same transverse plane as said bulkheads, so that the bracing effect of the tensional means and rings is unified to constitute an integrated transverse girder for the entire hull structure.

In the example shown, centered rings 12 serve as connecting means for tension wires 11 that radiate from said rings in the transverse plane of the bulkheads 9. These tension wires 13 may be pocketed within the bulkheads, and the latter may be composed of triangular shaped sections, sewn together, to thereby form the pockets between the overlapping portions of adjacent sections.

The rings 8 are each provided with an annular groove 14 at their inner surfaces, to contain a metallic hoop 15, which serves as an anchorage for the outer ends of the tension wires 13; and bolts 16, passed through radial apertures 17 provided in the rings 8 and shell 1, have terminal eyes 18 that engage said hoop 15. Spacer blocks 19 are provided at suitable distances apart between the shells 1 and 5, to maintain their true concentric relation.

Variations within the spirit and scope of my invention are equally comprehended by the foregoing disclosure.

I claim:—

1. A dirigible hull composed entirely of a number of layers of spiraled ply-wood strips, with only lateral reinforcing means, the strips of succeeding layers being spiraled oppositely, adjacent strips of each layer having scarfed edge relation.

2. A dirigible hull structure that is inherently capable of absorbing all longitudinal stresses consisting entirely of a number of layers of spiraled ply-wood strips, with only lateral reinforcing means, the strips of succeeding layers being spiraled oppositely, adjacent strips of each layer having scarfed edge relation.

3. A dirigible hull structure that is inherently capable of absorbing all longitudinal stresses, consisting entirely of a number of layers of spiralled ply-wood strips, the strips of succeeding layers being spiralled oppositely, adjacent strips of each layer having scarf'd edge relation, and internal rings to serve as peripheral stiffening means.
- 10 4. A dirigible hull structure that is inherently capable of absorbing all longitudinal stresses consisting entirely of a number of layers of spiralled ply-wood strips, the strips of succeeding layers being spiralled oppositely, adjacent strips of each layer having scarf'd edge relation, internal rings to serve as peripheral stiffening means, and bulkheads lying in the transverse plane of the rings.
- 15 5. A dirigible hull structure that is inherently capable of absorbing all longitudinal stresses and some of the transverse stresses consisting entirely of a number of layers of spiralled ply-wood strips, the strips of succeeding layers being spiralled oppositely, adjacent strips of each layer having scarf'd edge relation, and internal rings to serve as peripheral stiffening means.
- 20 6. A dirigible hull structure that is inherently capable of absorbing all longitudinal stresses and some of the transverse stresses consisting entirely of a number of layers of spiralled ply-wood strips, the strips of succeeding layers being spiralled oppositely, adjacent strips of each layer having
- scarfed edge relation, internal rings to serve as peripheral stiffening means, and bulkheads lying in the transverse plane of the rings.
- 25 7. A dirigible hull structure that is inherently capable of absorbing all longitudinal stresses consisting entirely of a number of layers of spiralled ply-wood strips, the strips of succeeding layers being spiralled oppositely, adjacent strips of each layer having scarf'd edge relation, internal rings to serve as peripheral stiffening means, bulkheads lying in the transverse plane of the rings, and radial tension members engaging the rings to serve as suspension means and to stiffen the bulkheads.
- 30 8. A dirigible comprising a hull structure composed entirely of a number of layers of spiralled ply-wood strips, the strips of succeeding layers being spiralled oppositely, and an outer shell of similar material and structure, spaced from the hull.
- 35 9. A dirigible comprising a hull structure composed entirely of a number of layers of spiralled ply-wood strips, the strips of succeeding layers being spiralled oppositely, an outer shell of similar material and structure, spaced from the hull, and intermediate connecting means to maintain the spaced relation of the hull structure and outer shell.

Signed at the borough of Manhattan in the city, county, and State of New York this 18th day of July, A. D. 1921.

THOMAS R. MACMECHEN.
